HENRY B. ADAMS, OF NEW YORK, N. Y.

Letters Patent No. 88,598, dated April 6, 1869.

IMPROVEMENT IN FLUTING-MACHINES.

The Schedule referred to in these Letters Patent and making part of the same.

Be it known that I, HENRY B. ADAMS, of the city, county, and State of New York, have invented a new and useful Improvement in Fluting-Machines, and that the following is a full and clear description thereof, reference being had to the annexed drawings, of which—

Figure 1 represents a front view of a machine containing my improvement, and

Figure 2, an end view.

Heretofore, fluting-machines were made of two fluted revolving rollers, either both in fixed bearings, or the lower one in fixed bearings, and the upper one hung in a frame, which was capable of being lowered and raised, either by set-screws, or by hand-levers.

Both the set-screws, as well as the hand-levers, involved a great loss of time of the operator, as it was necessary for him to use one of his hands to raise or lower the upper roller, a fact which often proved detrimental to the goods, if said goods were kept too long in contact with the hot rollers.

In order to avoid this danger, and provide an instantaneous motion for the separation of the two fluted rollers, I arrange the upper one, *a*, in fixed bearings in a frame, *b*, and the lower one, *c*, in bearings which are attached to a frame, *d*, and this frame *d* is made to slide up and down, by having a stem, *e*, in the centre of its lower side, which is guided straight up and down in a box, *f*, fixed to the main frame *b*, and the motion of raising and lowering the frame *d*, and its roller *c*, is obtained by a lever, *g*, whose fulcrum is at *h*, in about the centre of the said lever.

Both ends of the said lever *g* are arranged with slots, as clearly shown in fig. 1, to receive a strap, *k*, which reaches down to the floor, where, by means of a loop,

or treadle, attached thereto, the lever can be worked by the operator's foot.

This lever *g* also contains a projection at its upper edge, which enters the guide-box *f*, and is capable of raising the slide *d*, and its roller *c*, by abutting against the stem *e*.

The operator can attach the strap *k* to either end of lever *g*. If he fixes the said strap to the left-hand end, as shown in fig. 1, there is a spring, *l*, required, to bear upon the opposite end, which spring serves to force the left-hand end of the lever up, and so lift the lower roller. Then the operator separates the two rollers, by pulling the strap down by his foot, and, if he fixes the said strap to the right-hand end of lever *g*, then the spring *l* must be turned sidewise, out of contact with the lever. Then the operator raises the lower roller, by forcing the strap down by his foot, and he separates the two rollers from each other by lifting his foot, as the lower roller, and its slide *d*, will drop by their own gravity.

In both cases the motion is instantaneous, and performed by the operator without taking his hands off the work.

Having now fully described my invention,

What I claim therein as new, and desire to secure by Letters Patent, is—

The lower movable roller *c*, hung in a sliding frame, *d*, and the double-ended lever *g* and strap *k*, arranged and operated substantially as described.

HENRY B. ADAMS.
